United States Patent Office

Des. 181,595
Patented Dec. 3, 1957

181,595

FAUCET

Edward S. McLean, Wilmington, Del., assignor to Speakman Company, Wilmington, Del.

Application February 4, 1957, Serial No. 44,739

Term of patent 14 years

(Cl. D91—3)

FIG.1

I claim:

The ornamental design for a faucet, as shown.
